[57] **CLAIM**

The ornamental design for a blade medallion for a ceiling
fan, as shown and described.

DESCRIPTION

FIG. 1 is a top perspective view of the blade medallion for
a ceiling fan;

FIG. 2 is a top plan view thereof;

FIG. 3 is a front view thereof;

FIG. 4 is a right side view thereof;

FIG. 5 is a back view thereof;

FIG. 6 is a left side view thereof; and,

FIG. 7 is a bottom plan view thereof.

The broken line showing of environmental structure in FIG.
1 is for illustrative purposes only and forms no part of the
claimed design.
